ATTORNEYS.

UNITED STATES PATENT OFFICE.

HARRY W. BROOKS, OF BRADDOCK, PENNSYLVANIA.

TROLLEY-STAND.

SPECIFICATION forming part of Letters Patent No. 633,786, dated September 26, 1899.

Application filed July 6, 1899. Serial No. 722,929. (No model.)

To all whom it may concern:

Be it known that I, HARRY W. BROOKS, a citizen of the United States of America, residing at Braddock, in the county of Allegheny and State of Pennsylvania, have invented certain new and useful Improvements in Trolley-Stands, of which the following is a specification, reference being had therein to the accompanying drawings.

10 This invention relates to certain new and useful improvements in trolley-stands for street railways and tramways.

The invention has for its object to dispense with the present swiveled trolley-stand that is now commonly employed; furthermore, to construct a stand carrying a trolley-pole mounted in a universal joint that will permit the trolley-wheel to be moved in any direction desired.

15 20 The invention further aims to construct a stand of this class that will be extremely simple in its construction, strong, durable, and highly efficient in its operation; furthermore, one that may be manufactured at a comparatively small cost.

With the above and other objects in view the invention finally consists in the novel construction, combination, and arrangement of parts to be hereinafter more fully described, 25 and specifically pointed out in the claims.

In describing the invention in detail reference is had to the accompanying drawings, forming a part of this specification, wherein like numerals of reference indicate corresponding parts throughout the several views, 35 in which—

Figure 1 is a side elevation of my improved trolley-stand. Fig. 2 is a vertical sectional view taken on the line 2 2 of Fig. 4. Fig. 3 40 is an inverted plan view of Fig. 1. Fig. 4 is a top plan view of the same.

Referring to the drawings by reference-numerals, 1 indicates a suitable base which is rigidly secured to the top of the car 2 by 45 means of screws 3.

The reference-numeral 4 represents recesses formed in the under face of the base 1 for the reception of screws 5, extending upwardly into the binding-posts 6, said screws 50 being connected by a wire 7, forming part of the electric circuit.

The reference-numeral 8 indicates a bell-

shaped casing, said casing having secured thereto standards 9, said standards carrying a swiveled sleeve 10, said sleeve having pivotally secured therein a head 11 of the socket 12, in which is mounted the trolley-pole 13, said head 11 having centrally arranged therein an aperture 14, having at its upper extremity an enlarged recess 15 for the reception of a cone-bearing 16, carrying a shank 17, extending through the aperture 14, said shank having formed at its lower extremity and integral therewith a ring 18, to which is attached a coil-spring 19, extending downwardly through the base 1 and secured to said base by means of the nut 20, operating in the recess 21, formed centrally in the under face of said base. The said spring 19 extends through the bell-shaped casing 8.

70 It will be noted that by forming the universal joint herein described and set forth the trolley-pole will be permitted to operate in any desired direction, this being a decided advantage when traveling through switches and curves, thus allowing the trolley-wheel to follow the course of the wire, overcoming the objectionable feature that is now experienced of the trolley-wheel becoming dislodged from the wire when traveling over abrupt curves and switches.

75 From the above description the many advantages of my improved device will be readily apparent.

It will be noted that various changes may 80 be made in the details of construction without departing from the general spirit of my invention.

Having thus fully described my invention, what I claim as new, and desire to secure by 90 Letters Patent, is—

1. In a trolley-stand, the combination of a base, a casing, standards secured thereto carrying a swiveled sleeve, a socket swiveled in said sleeve, a trolley-pole secured in said sleeve, and a spiral spring connecting said socket and said base, substantially as described.

2. In a trolley-stand, the combination of a base, standards secured to said base, a swiveled sleeve secured in said standards, a socket swiveled in said sleeve, and a spiral spring connecting said socket and said base, substantially as described.

3. In a trolley-stand, the combination of a suitable base, a bell-shaped casing mounted on said base, standards secured to said base and said bell-shaped casing, a swiveled sleeve 5 mounted near the upper extremity of said standards, a swiveled socket secured in said sleeve, an inverted cone-shaped bearing secured in said socket, a spiral spring forming connections between said cone-shaped bear-

ing and said base, all parts being arranged to and operating substantially as herein shown and described.

In testimony whereof I affix my signature in the presence of two witnesses.

HARRY W. BROOKS.
